United States Patent Office

Des. 187,919
Patented May 17, 1960

187,919

SETTEE

Chester J. Barecki, Grand Rapids, Mich., assignor to
American Seating Company, Grand Rapids, Mich., a
corporation of New Jersey

Application February 11, 1959, Serial No. 54,566

Term of patent 14 years

(Cl. D15—11)

Fig. 1

Fig. 2

Fig. 3

Figure 1 is a front perspective view of a settee showing my new design;

Figure 2 is an end elevational view thereof;

Figure 3 is a central, vertical sectional view of one of the molded seat buckets; and

Figure 4 is a rear elevational view of the settee as shown in Figure 1.

I claim:

The ornamental design for a settee, substantially as shown.
